COUPLING DEVICE

Application filed April 21, 1930. Serial No. 446,128.

In radio frequency amplifiers and similar apparatus it is necessary to regulate the amount of energy transfer from one part of the electrical system to another. This regulation may be accomplished in steps or by a continuously variable means; the latter being considered the most desirable for use in broadcast radio receivers. It is with this latter type of continuous volume control that 10 this invention deals primarily, although its principle applies to "step by step" regulators as well. The features and advantages of a volume control system embodying all the principles of the present invention will be 15 made clear by an analysis of the methods now commonly used for volume control in broadcast receivers.

In the great majority of radio sets volume control is accomplished by means of a variable resistor of the sliding contact type; generally a slide-wire rheostat or potentiometer. Now, strictly speaking every slide-wire instrument is a non-continuous (step by step) instrument, the size of the step being 25 the resistance of a single full turn of wire from contact point to contact point. While the magnitude of the resistance of one of such single turns of wire between the contact points is insignificant at regions of high 30 total resistance, this dis-continuity becomes very disturbing at the zero end of rheostats. It is a well known fact that most of the powerful radio sets now on the market are 35 unable to reduce to a sufficiently low value the signals from high powered local transmitters, the volume jumping from zero to an undesirably high amount with the most minute adjustment that can be made.

This dis-continuity is theoretically avoided 40 in certain carbon composition rheostats which vary the contact point either directly by a sliding metal spring, or in an alternative form indirectly by a curved disc rolling over the carbon disc under the pressure of a sliding spring. All rheostats, however, share the

big drawback of relying upon the electrical contact maintained by a mechanical spring pressure. It has been found in practice that all such contacts deteriorate, through corrosion of the metal surfaces, wearing of bearings, aging of carbon, loosening of springs, and other effects. The results of this deterioration of rheostats results in the characteristics highly objectionable crackling noises heard in all radios sets after a few months 50 of use. In addition, it will be shown below that rheostat control shares with other known controlling means, the disadvantage of changing the resonant frequency of tuned circuits. As an alternative to volume control by 55 resistance variation, there remains the reactance control, which involves the variation of inductance or capacity. While it is true that the variation of reactance can be accomplished without discontinuity and without 60 sliding pressure contacts, by virtue of the use of the well known variometers, vario-couplers, and variable condensers; yet, this scheme has the disadvantage of changing the tuning of the circuits as the reactances 65 are varied.

Thus, if a variation in reactance is used to detune a loosely coupled resonant circuit, an effective volume control will be had, but only at the cost of selectivity and quality. 70 The slight detuning necessary for the desired change of energy transfer is sufficient to cause objectionable side-band cutting in a receiver of audio frequency modulated radio frequency signals.

Moreover, in receivers of average sharpness of resonance this slight detuning to effect volume control will also shift the resonance point of the detuned circuit beyond the 75 10 kilocycle tuning channel assigned to the broadcasting stations, thereby tending to bring in disturbing signals from adjacent signal channels.

Again, if the variable reactance is used as a coupling reactance, for instance between 80

the antenna circuit and the first tuned radio frequency stage, or between a plate circuit of one amplifier tube and a tuned grid circuit of a succeeding amplifier tube, it might appear offhand that the variation of coupling will cause variation in volume without detuning. As a practical matter, this is not so for the following reasons: The primary (or driving) circuit, containing the antenna or the plate impedance of a tube, has a definite reactance of its own; and the same coupling reactance which transfers varying amounts of energy from the primary circuit into the secondary, also transfers into the secondary varying fractions of the primary impedance. If Z_1 is the primary impedance, M the common coupling impedance which may be inductive, capacitive or even resistive, then the impedance (Z_2) transferred into the secondary circuit from the primary is:

Equation (1)

$$Z_2 = \frac{M^2}{Z_1}$$

Consequently, we cannot vary either M or Z_1 without simultaneously varying Z_2 , thus detuning the secondary circuit. To a lesser degree, this is also true for most of the above mentioned volume controls based upon resistance variation as described above. If the circuit, the resistance of which is changed, is in any way coupled to a tuned circuit, it changes the resistance of that tuned circuit; and since the resonance frequency F of a circuit containing a resistance R , an inductance L , and a capacitance C is expressed by

Equation (2)

$$F = \frac{1}{2\pi} \sqrt{\frac{1}{LC} - \frac{R^2}{4L^2}}$$

We see from Equation (2) that the tuning is affected by a change in R .

It is therefore an object of this invention to provide a volume control, utilizing a continuously variable reactance designed to effect the energy transfer from a primary driving circuit into a secondary driven circuit, one or both of which are tuned to the frequency of the desired signal, without such variations in reactance changing the tuning of the coupled circuits.

It is a further object of this invention to provide a volume control utilizing a variable reactance in combination with a compensating reactance, both of which are constructed and arranged to give volume control without changing the tuning.

It is also now well known and understood in this art that the tendency of a radio frequency amplifier to go into self oscillation depends, among other things, upon the value of the plate inductance of each amplifier stage.

It has been found that a radio receiving set constructed in accordance with the principles of this invention has the further advantage that the tendency toward self oscillation of the amplifier stage is greatly reduced by virtue of the fact that variations in coupling and tuning which ordinarily alter the value of the plate inductance of the amplifier tube do not effectively alter the value of the plate inductance of the amplifier tube of a system constructed in accordance with this invention.

It is therefore a further object of this invention to provide, in a radio receiver utilizing radio frequency amplifiers, a means for varying the tuning of the amplifier stages and also for varying the amount of energy transfer between stages, without producing attendant undesirable variations in the plate impedance of the amplifier tubes.

Further, it is an object of this invention to provide a radio receiving set employing radio frequency amplifiers, in which volume control is effected by variation of certain reactances, while at the same time compensating the tuned circuits for such variations, in such a way as to avoid detuning and to avoid also the tendency toward self oscillation of the amplifiers.

These and other objects of the invention will be readily apparent to those skilled in the art from the following description taken in connection with the accompanying drawings in which:

Fig. 1 is a diagrammatic representation of a system embodying the principles of this invention; and

Fig. 2 is a modification.

Briefly, the objects of this invention are realized by virtue of a compensating reactance which is coupled to the variable reactance which effects the volume control in such a way that the detuning action of the volume control per se is compensated for by the auxiliary reactance.

Let us assume, for example, that the volume control consists of a variable mutual inductance M coupling a driving circuit having an impedance Z_1 and a tuned secondary circuit. Let us assume further that the compensating circuit has an impedance Z_3 and is coupled to the tuned circuit by a variable mutual inductance N . I have found that compensation is achieved if the following relationship exists:

Equation (3)

$$\frac{M^2}{Z_1} + \frac{N^2}{Z_3} = \text{constant}$$

or:

Equation (4)

$$N = \sqrt{\text{constant} - \frac{M^2 Z_3}{Z_1}}$$

Referring in detail to Fig. 1 of the drawing there is shown an arrangement embodying the principles of this invention. The primary circuit in this case illustrated consists of the plate impedance of an amplifier tube P in series with the self inductance of a coupling coil m . The battery B for supplying the high potential to the tube P is shunted by a condenser k , thus eliminating the resistance of the battery B to the flow of radio frequency currents in the plate circuit. The secondary circuit comprises the input circuit of a second amplifier tube Q . This input circuit includes the inductance L which is variably coupled to the coil m . A compensating coil n is coupled to the coil L . Since in the primary circuit the plate impedance is equivalent to a resistance r_p shunted by the plate capacity c_p , the compensating circuit also includes a resistor r_n and parallel with a condenser c_n . The coils m and n are mounted upon a common shaft so that the coupling between the coils m and L and n and L may be simultaneously varied. That is, as the coupling between m and L is reduced the coupling between n and L is increased. To obtain the desired variations in coupling between the coils any suitably shaped variometers may be used; or alternatively, any suitably shaped cam structures may be used to provide for variations of coupling in accordance with any desired predetermined law. The amplifier tube Q is tuned by means of the variable condenser S . The condenser S may be one of a gang of condensers used to vary the tuning of a cascaded radio frequency amplifier.

In this event all of the condensers are usually operated from a common shaft by the well known uni-control means. It is also contemplated by this invention that the uni-control for the variable tuning condensers be coupled to the variable coupling means, so that variable coupling may be had with variable tuning, the compensating impedance serving to permit simultaneous variations in coupling and tuning by a single means. It will be understood that provision should be made whereby the tuning variations and coupling variations including the compensating means may be made either together or separately, and that when they are made together the coupling is varied with the tuning to give the most efficient transfer of energy, whereas when it is desired to vary the coupling as a volume control means alone the tuning adjustment should not be altered. It will be understood, of course, that in the case where I vary the coupling and tuning together by a single means, my compensating device functions to counteract changes in impedance caused solely by changes in coupling and therefore the changes in coupling do not affect the operation of the uni-control tuning adjustments. I have shown dia-

grammatically in Fig. 1 the variable elements of the coupling coils, tuning condensers, and compensating device as being coupled together for concomitant operation. In practice any of the well known mechanical arrangements may be used. To permit independent adjustment of the variable coupling means and the variable tuning means, any suitable mechanical arrangement may be used.

The constants of the compensating circuit of Fig. 1 are adjusted to maintain the following relation:

Equation (5)

$$N : r_n : C_n = M : r_p : C_p$$

Furthermore, the relative positions on the control shaft of the coils m and n are so chosen that their mutual inductances to L remain in accordance with Equation (4).

Referring to Fig. 2, another embodiment of the same invention is shown. The driving circuit in this case is the antenna A . The coupling impedance is the small variable capacity c_1 . The secondary tuned circuit consists of a capacity C and an inductance L . The compensating coupler is the small variable capacity c_2 which is mounted upon the same rotor shaft as the capacity c_1 and is designed to increase in capacity as c_1 decreases.

The electrical constants of the antenna are simulated in the compensating circuit by a capacity c_n (about 2000 m. m. f.) in series with a resistance R_n (about 25 ohms) and if necessary a small inductance L_n (about 20 microhenries).

As explained above the values are adjusted so that the variations of the compensating circuit counteract those of the antenna circuit. This is most easily achieved by making:

Equation (5a)

$$C_n = C_a$$

where C_a = capacity of antenna or primary circuit

Equation (5b)

$$R_n = R_a$$

where R_a = resistance of antenna or primary circuit

Equation (5c)

$$L_n = L_a$$

where L_a = the inductance of the antenna or primary circuit

Equation (3a)

$$C_1 = \text{constant} - C_2$$

It is evident that there are many possible variations of the circuit described above which can be designed by any one skilled in the art. For instance, the impedance of the primary of two coupled circuits is affected

for coupling variations by the secondary impedance in the same way as the secondary is affected by the primary. In this event, it is merely necessary to apply the compensating circuit to the primary circuit, applying the principles outlined above, in stead of applying the compensating circuit to the secondary. It is also within the scope of this invention to apply the compensating circuit both to the primary and the secondary circuits following the principles already mentioned.

Having thus described my invention, what I claim is:

15. 1. A variable coupling device comprising in combination, a first tuned circuit, a second circuit coupled thereto, a variable reactance connected to said first circuit for varying the coupling of said circuits, said variation in coupling producing in said tuned circuit a change in the tuning thereof, a third circuit variably coupled to said first circuit, and means for simultaneously varying the coupling between said first and second circuits and said second and third circuits, in such a manner as to maintain substantially constant the tuning of said first circuit.

20. 2. A variable coupling device comprising in combination, a first tuned circuit, a second circuit coupled thereto, a variable reactance connected to said first circuit for varying the coupling of said circuits, said variation in coupling producing in said tuned circuit a change in the tuning thereof, a third circuit variably coupled to said first circuit, said third circuit containing reactance elements simulating said second circuit, and means for simultaneously varying the coupling between said first and second circuits and said second and third circuits, in such a manner as to maintain substantially constant the tuning of said first circuit.

35. 3. A variable coupling device comprising a first tuned circuit having an inductance and capacitance therein, a second circuit variably coupled to said first circuit and having an inductance, a capacitance, and a resistance contained therein, means to vary the coupling of said two circuits, whereby there is produced in said first circuit a change in the value of the inductance contained therein, and means to compensate for the said change in inductance.

45. 4. A variable coupling device comprising a first tuned circuit having an inductance and capacitance therein, a second circuit variably coupled to said first circuit and having an inductance, a capacitance, and a resistance contained therein, means to vary the coupling of said two circuits, whereby there is produced in said first circuit a change in the value of the inductance contained therein, and means to compensate for the said change in inductance, said first mentioned means and said last mentioned means being

mechanically coupled together for concomitant operation.

5. A variable coupling device comprising a first tuned circuit having an inductance and capacitance therein, a second circuit variably coupled to said first circuit and having an inductance, a capacitance, and a resistance contained therein, means to vary the coupling of said two circuits, whereby there is produced in said first circuit a change in the value of the inductance contained therein, a third circuit variably coupled to said first circuit, and means for simultaneously varying the coupling between said first and second circuits and said second and third circuits, in such a manner as to maintain substantially constant the tuning of said first circuit.

6. A variable coupling device comprising a first tuned circuit having an inductance and capacitance therein, a second circuit variably coupled to said first circuit and having an inductance, a capacitance, and a resistance contained therein, means to vary the coupling of said two circuits, whereby there is produced in said first circuit a change in the value of the inductance contained therein, a third circuit variable coupled to said first circuit, said third circuit containing reactance elements simulating said second circuit, and means for simultaneously varying the coupling between said first and second circuits and said second and third circuits, in such a manner as to maintain substantially constant the tuning of said first circuit.

7. In a radio receiver having a first radio frequency circuit, and a second radio frequency circuit coupled thereto, the combination with a volume control device for regulating the volume of sound reproduced by said receiver, said device including a variable coupling means which introduces variations in tuning in one of said circuits as the coupling is varied to effect volume control, and means to compensate for such variations in tuning in such a way as to maintain the said tuning independent of said variations in coupling.

8. In a radio receiver having a first radio frequency circuit, and a second radio frequency circuit coupled thereto, the combination with a volume control device for regulating the volume of sound reproduced by said receiver, said variable coupling device including a condenser having two separated fixed plates and a single rotary plate cooperating therewith, the plates being so arranged that an increase in capacity between two of such plates is accompanied by a decrease in capacity between one of said two plates and the third plate, and means for moving said rotary plate to control the volume of sound reproduced by said receiver by varying the coupling between said two circuits, said variations in coupling tending to introduce incidentally variations in tuning of one of said circuits, and said variations in tuning being

compensated for by two of the plates of said coupling device, in such a way as to maintain substantially constant the tuning of said circuits as the coupling therebetween is varied.

- 5 9. In a radio receiving system including an antenna circuit, a three-plate condenser having two of its plates connected in said antenna circuit, a radio frequency amplifying circuit, a third plate of said condenser
10 being connected to said last mentioned circuit, means to vary the position of said third plate with respect to said other two plates, whereby simultaneously to vary the coupling between said antenna circuit and said radio
15 frequency amplifier and to maintain substantially constant the tuning of said antenna circuit.

In witness whereof I hereunto affix my signature.
